BAND-BRAKE ADJUSTING MECHANISM

Joseph Yoxall, Deganwy, North Wales, assignor
to Propello Inventions Limited, London, Eng-
land, a British company

Application April 10, 1935, Serial No. 15,671
In Great Britain June 29, 1934

10 Claims. (Cl. 188—79.5)

The present invention relates to mechanism for automatically taking up wear in band-brakes.

The present invention has for its object to provide an improved construction of adjusting mechanism.

According to the present invention self-adjusting mechanism for taking up wear in band-brakes comprises a drum, a brake-band, members movable to apply said brake-band on said drum, a bipartite member capable of alteration in length by screwed adjustment of its parts, two axially separated self-lapping coil springs of opposite hand mounted one on each part of said bipartite member and serving, when the brake-band becomes worn a predetermined amount to produce alteration in length of said bipartite member, upon fully applying and releasing the brake-band.

In order that the invention may be readily understood, the same will now be described with reference to the accompanying drawings which illustrate, by way of example, one embodiment thereof.

In the drawings:—

Figure 1 shows partly in cross-section and partly in elevation the adjusting mechanism as applied to an external contracting band-brake; Figure 2 is a cross section taken along line 2—2 of Figure 1.

Figs. 3, 4, 5, 6 and 7 are perspective views of various disassembled parts of the right-hand brake applying unit seen in Fig. 1; and

Fig. 8 is a perspective view of the brake bands and some associated parts illustrating the relative position of such bands.

Reference numeral 3 indicates a casing surrounding the brake-band assembly, 53 is an annulus or drum to be braked, and 60, 61 are two brake-bands encircling the said drum 53. The two brake-bands each extend around the drum 53 and are situated side by side thereon, the band 61 being attached to two relatively movable segmental members 103, 104 by means of rivets. As seen in Figure 1 brake-band 60 is to the rear of brake-band 61, the former being visible only at the gap between members 103, 104. Desirably the brake-lining proper 61 is mounted upon a flexible metallic strip 101, which is itself riveted to the members 103, 104. Similarly, brake-band 60 is mounted upon metallic strip 102, attached at its ends to segmental members 99, 100. Application of the two brake-bands 60, 61, to the drum 53 is effected by means of two toggle systems or units, one for each band. It is to be explained that the actuation of the two toggles

is effected by means pressing against links in each of them; these means may be manually operated, or operated by a pedal, or as shown, by hydraulic means. The hydraulic means comprise a cylinder 64 into which pressure-fluid can be admitted from a conduit 105 by way of orifices 70 and 74 when a rotary valve member 43 constituting the conduit is turned so that the orifices 70 and 74 coincide. When pressure-fluid is admitted into cylinder 64 it exerts pressure against two pistons 106, 107 therein, which pistons are in permanent contact with rollers 108, 109 each attached to one member of the two toggle systems. A spring 110 maintains contact between pistons 106, 107 and rollers 108, 109.

Attention is now particularly directed to the right-hand toggle-system shown in Figure 1, which system is also shown in end elevation in Figure 2, and in disassembled condition in Figure 3.

This toggle system is constituted by three elements, viz., a long arm 111, and two short struts 112, 113. Arm 111 actually consists of two plates 111, 111a, riveted together by means of bridge pieces 114, 115; holes are drilled in the plates 111, 111a to accommodate a pin 118 by which the arm 111 is pivotally anchored in a grooved member 119 fixed to the casing 3. Strut 113 consists of a short steel wedge-shaped member, one end, 120, of which is forked so as to fit upon bridge piece 115 and be capable of slight swinging movement thereon. Strut 112 is constituted by three elements 121, 122, 123 of which 121 is a flattened steel member having one end 124 rounded to form a bearing surface and provided with cheeks 125, 125' adapted to prevent the end 124 from slipping laterally from a shaped bearing surface formed on segmental member 104 against which member 121 bears. The other end 126 of member 121 is tubular and is provided with a coiled spring 127 gripped thereto by screw 128, and adapted to co-operate with a surface of the correspondingly shaped element 122. This element 122 comprises a rod having at one end a portion 129 of reduced diameter adapted to fit the tubular end 126 of member 121, and formed at its other end 130 with an internal screw-thread 131. Over the end 130 there is slipped a tubular member 132 provided with wings 133, 134 and with a coil spring 135 gripped by a screw 136 mounted in wing 133, member 132 being retained in position on element 122 by a sprung-on ring 137 fitting in a groove therein. Element 123 comprises a castor 138 carrying the roller 109, already referred to, and provided with a threaded

extension 139 adapted to be screwed into the screw-thread 131 in member 122.

It will be noted that coil springs 135, 127 are of opposite hand, spring 135 being adapted to grip upon the surface of member 122 by a self-lapping action when (in the assembled form of the device shown in Figure 1 as viewed from above) member 132 is turned clockwise relatively to member 122, and spring 127 exerting a gripping action on member 122 when attempt is made to turn it anti-clockwise relatively to member 121, as viewed in Figure 2.

In Figure 1 the right-hand toggle is shown in assembled form, and in the condition in which the brake-band is fully applied after it has undergone some wear.

It will be seen that in order to apply the band 60 fully it has been necessary for piston 107 to shift members 112, 113 of the toggle into a position in which they are nearly coincident with the third member 111 of the toggle, the movement of members 112, 113 being limited by a stop 143 since brake band 61 is shown in Fig. 1 as fully applied (and being also substantially worn), it is to be observed that member 123 of the brake mechanism is hard up against stop 143 which is in the form of a bar held between plates 111, 111a: such an amount of movement of the piston, and of roller 109 can only occur when the brake-band has worn (since, if the band is not worn then the same becomes fully applied on to its drum 53 by only a slight rightward movement of member 123, in which event said member does not reach stop 143), and when this movement takes place wing 133 is caused to strike against plate 111a and turn member 132 on member 122, thus causing wing 134, which has by this time passed to the right of plate 111a as seen in Figure 2, to rise, so that upon release of the brake-band and movement of roller 109 and related parts to the left, it is wing 134 that is caused to strike against plate 111a and turn member 132. The first turning movement of member 132 (caused by a full rightward movement of roller 109 with the brake-band worn) causes member 132 to turn freely on member 122 in an anticlockwise direction as viewed in Figure 2, coil spring 135 allowing this free movement and coil spring 127 preventing member 122 from following the movement of member 132; the second turning movement of member 132 (caused by the return of roller 109 upon release of the brake-band) causes coil spring 135 to bind on the surface of member 122 and turn it in a clockwise direction, as viewed in Figure 2, said movement causing coil spring 127 to release its grip on member 122. This turning movement causes member 122 to be screwed a slight distance along threaded extension 139 whereby the strut 112 of the toggle is lengthened and wear in the brake-band is compensated for. If piston 107 and roller 109 are moved repeatedly to and fro, when the brake-band is worn, strut 112 is lengthened slightly at each return movement until the brake-band has been adjusted to such a tightness that upon the normal movement of roller 109 the band is fully applied and member 132 is not caused to reach a position during full application of the brake in which wing 133 strikes plate 111a. When this condition is reached, no further adjustment of the brake-band takes place, but immediately the same wears and permits member 132 to move rightwardly a sufficient distance to allow wing 133 to

strike plate 111a, then automatic adjustment takes place.

It may be noted that if a new brake band is inserted in a band-brake according to the invention, the same may be automatically adjusted to exactly the right tension by merely applying and releasing the brake a number of times.

The construction of the left-hand toggle mechanism shown in Figure 1 is very similar to that of the right-hand toggle except that the roller 108 is attached to arm 140 of the toggle, whilst the relative position thereof to that of elements 141, 142 (corresponding to elements 112, 113 of the right-hand toggle) is reversed, element 141 being pivotally anchored at 141a, to the casting 3. It is to be observed that when brake band 60 is slack on drum 53, roller 108 of the left hand toggle mechanism is to the right of the position shown in Fig. 1; and that in such "off" position of the band the angle between members 140 and 142 of the mechanism is more acute than as shown, so that arm 140 forms the base of a triangle whose other two sides are constituted by elements 141, 142. Upon reflection it will be seen that by pressing roller 108 to the left and holding anchorage pin 141a the same effect is obtained as would occur if roller 108 were held and pin 141a were pressed to the right which latter action is substantially identical with the action, described above, of the right hand toggle mechanism of Figure 1. In each toggle mechanism seen in Fig. 1 there is provided a torsion spring (150 in the left hand mechanism, 151 in the right hand mechanism of Fig. 1), the action of which is to tend to brake the toggle in each case, and so to maintain the corresponding brake band slack on drum 53.

The duplicate and substantially symmetrical arrangement of brake bands 60, 61, and of the control means therefor, as shown, provides a balanced assembly as regards braking torque.

It will, of course, be understood that the present invention can, with suitable modifications to the connections between the toggles and brake bands, be applied as well to an internal expanding brake as to an external contracting brake.

What I claim is:

1. Self-adjusting mechanism for taking up wear in band-brakes comprising a drum, a brake-band, members movable to apply said brake-band on said drum, a bipartite member capable of alteration in length by screwed adjustment of its parts, two axially separated self-lapping coil springs of opposite hand mounted one on each part of said bipartite member and serving, when the brake-band becomes worn a predetermined amount to produce alteration in length of said bipartite member, upon fully applying and releasing the brake-band.

2. Self-adjusting mechanism for taking up wear in band-brakes comprising a brake-band, a substantially triangular structure formed of an inextensible member consisting of two plates held together by bridge pieces one of which pieces bears against one end of said brake band, a member adjustable in length, and a strut, said strut and said adjustable member being held between the free end of said brake-band and the other of said bridge pieces.

3. Self-adjusting mechanism for taking up wear in band-brakes comprising a brake-band, a substantially triangular structure formed of an inextensible member connected to one end of said brake-band, a bipartite member adjustable in

length, two axially separated self-lapping coil springs of opposite hand mounted one on each part of said bipartite member and serving, when the brake-band becomes worn a predetermined amount to produce alteration in length of said bipartite member, upon fully applying and releasing the brake-band, and a strut, said strut and said adjustable member being held between the free end of said brake-band and said inextensible member.

4. Self-adjusting mechanism for taking up wear in band-brakes comprising a casing, a brake-band having a gap between its ends, a substantially triangular structure formed of an inextensible member connected to one end of said brake-band, a member automatically adjustable in length anchored to said casing, and a strut, said strut and said adjustable member being held between the free end of said brake-band and said inextensible member.

5. Self-adjusting mechanism for taking up wear in band-brakes comprising a pair of brake-bands each having a gap between its two ends both bands being arranged around a single drum 25 to be braked with said gaps substantially diametrically opposite each other, a plurality of sets of members movable to apply said brake-bands substantially equally on said drum a plurality of bipartite members capable of alteration in 30 length by screwed adjustment of their parts, and one-way clutching means mounted on said bipartite members serving, when the brake-bands become worn a predetermined amount to produce alteration in length of said bipartite members, and consequent adjustment of said brake-bands, upon fully applying and releasing the 35 brake-bands a requisite number of times.

6. Self-adjusting mechanism for taking up wear in band-brakes comprising a brake-band, 40 an anchored member, a bipartite member movable relatively thereto to apply the brake-band, said bipartite member being capable of alteration in length by screwed adjustment of its parts, two axially separated self-lapping coil springs 45 of opposite hand mounted one on each part of said bipartite member and serving, when the

brake-band becomes worn a predetermined amount to produce alteration in length of said bipartite member, upon fully applying and releasing the brake-band.

7. Self-adjusting mechanism for taking up 5 wear in band-brakes comprising a brake-band, a bipartite anchored member, a member movable relatively thereto to apply the brake-band, said bipartite anchored member being capable of alteration in length by screwed adjustment of its 10 parts, and two axially separated self-lapping coil springs of opposite hand mounted one on each part of said bipartite member and serving, when the brake-band becomes worn a predetermined 15 amount to produce alteration in length of said bipartite member, upon fully applying and releasing the brake-band.

8. For use in connection with brake-band applying mechanism, self-adjusting mechanism for taking up wear, comprising a substantially triangular structure formed of an inextensible member, a member adjustable in length, a pair 20 of self-lapping coil springs of opposite hand mounted on said adjustable member, and a strut.

9. For use in connection with band-brake applying mechanism, self-adjusting mechanism for taking up wear, comprising a substantially triangular structure formed of an inextensible member, a bipartite member adjustable in length, two axially separated self-lapping coil springs 25 of opposite hand mounted one on each part of 30 said bipartite member, and a strut.

10. Self-adjusting mechanism for taking up wear in band brakes comprising a casing, a brake band comprising two spaced ends, a substantially triangular structure formed of an inextensible member connected to one end of said brake band, a member adjustable in length and carrying two axially separated self-lapping coil springs 35 of opposite hand, one of said members being anchored to said casing, and a strut, said strut and said adjustable member being held between the free end of said brake band and said anchored member.

JOSEPH YOXALL. 45
